UNITED STATES PATENT OFFICE.

CHARLES ARTHUR EASTING, OF BIRMINGHAM, ENGLAND.

WIND-SCREEN FOR MOTORCYCLE SIDE CARS.

1,343,440.

Specification of Letters Patent. Patented June 15, 1920.

Application filed October 15, 1917. Serial No. 196,700.

To all whom it may concern:

Be it known that I, CHARLES ARTHUR EASTING, of 59 Abbey road, Warley Woods, Birmingham, in the county of Warwick, England, have invented a new and useful 5 Wind-Screen for Motorcycle Side Cars; and I do hereby declare the following to be a full, clear, and exact description of the same.

10 My invention comprises improvements in wind screens for motor cycle side cars and refers more particularly to that class of such screens which are of curved form in plan; the object of the present invention being to provide an improved and more effective screen for the specified purpose.

According to this invention I provide a transparent wind screen for motor cycle side cars, of curved form in plan mounted 20 normally in front of the rider and supported at its lower corners by brackets; said screen being pivotally mounted at a point below the bottom of said screen in such manner that it may be tilted over the passenger's head to form a protection against rain.

The invention further comprises an improved construction of flexible screen which is normally flat but can be temporarily bent 30 to a curved form.

Referring to the drawings:—

Figure 1. is a perspective view showing a screen according to this invention in position upon a side car.

35 Fig. 2. is a similar view showing the screen tilted as over the rider's head when traveling through heavy rain.

Fig. 3. is a side elevation of the screen.

Fig. 4. is a section at A—B in Fig. 3.

40 Fig. 5. illustrates the screen opened flat.

Fig. 6. illustrates the socket for securing the screen to the standard, removed.

Fig. 7. illustrates a modified construction of standard.

45 Fig. 8. is a vertical section through same including the screen locking pin.

Fig. 9 is a fragmentary view showing the screen support.

In carrying my invention into practice as 50 illustrated upon the accompanying drawings at Figs. 1-6, the screen is made from a sheet of celluloid or like material as 1 and around the edge of this screen a frame is secured. This frame may conveniently consist of a folded strip of leather or equivalent 2 surrounding a strip of spring steel 3,

the leather securing the spring steel to the celluloid being so arranged that the normally flat screen and frame may be bent to the desired curvature without destroying 60 the resiliency of the frame. Preferably the lower strip of the frame is of greater strength than the upper one so that when the screen is bent and held at the bottom the wall of the screen will be substantially vertical. 65

The end or vertical members of the screen frame are preferably of stout rigid metal as these are not bent in practice, being inclosed in similar leather containers as 4, and 70 they may be riveted to the horizontal members at the corners or otherwise secured thereto.

The leather framing strip at the bottom may be continued below the celluloid as 5 75 and provided with a series of press button members 6 to enable the apron 7 to be detachably secured thereto, the apron being preferably provided with a flexible strip of metal or wire to cause it to assume the same 80 shape as the screen when secured at the extremities; the wire being within the edge of the apron which is to be attached around the screen.

As shown means are provided for enabling the screen to be tilted to various angles, more particularly for the purpose of shooting off the rain when a hood is not in use, as seen in Fig. 2, such means consisting in pivoting the screen about a horizontal 90 axis. The standard comprises a lower member 10 bolted to the side car body as at 11; and an upper part 12 on which the socket 13 secured to the screen is placed and locked by the screw 14. A quadrant slotted member 15 with locking screw 16 may be disposed around the pivot 17 to enable the joint to be locked in any of its adjusted positions. Or any other equivalent arrangement may be employed. The screen may be provided with press buttons as 4^a whereby it may be fastened in the position shown in Fig. 2. 95

In the preferred form the screen when bent is of more or less semi-circular shape in 105 plan so as to provide side screens as well as a front screen and to offer a minimum of wind resistance.

The space between the screen and the front of the side car is closed by means of a suitable apron which may be conveniently secured to the flexible strip along the lower 110

edge of the screen frame previously referred to, and two points of the apron may then be attachable to the front of the side car to compensate for a longitudinal adjustment 5 of the screen position.

As will be clear from the description the screens being built flat can be readily stored and packed for transit, while their resiliency will enable them to be mounted equally effectively upon side cars of widely different 10 widths.

What I claim then is:—

1. A transparent wind screen for motor 15 cycle side cars comprising in combination a sheet of transparent flexible material; a flexible framework surrounding said transparent sheet, said framework having rigid vertical members and flexible horizontal members, said sheet and framework being 20 normally flat but adapted to be bent to a curved form, brackets on the side car body for holding said screen in its curved form; means whereby the said screen may be readily detached from the bracket so that 25 it will resume its normally flat condition when the passenger requires to leave or enter the side car; and means whereby the screen when held upon said bracket may be tilted over the passenger's head to form a 30 rain hood; substantially as and for the purpose specified.

2. A transparent wind screen for motor 35 cycle side cars comprising in combination a sheet of transparent flexible material bent to a curved form; a horizontally flexible but vertically rigid framework surrounding said transparent sheet, said sheet and framework being normally flat but adapted to be bent to a curved form; brackets on the 40 said side car body for holding said screen in its curved form; means whereby the screen may be readily detached from the bracket so that it will resume its normally flat position when the passenger requires to 45 leave or enter the side car and means whereby the screen when held upon said bracket may be tilted over the passenger's head to form a rain hood; means for locking the screen in various angularly adjusted positions; and means for adjusting the position of the screen vertically.

3. A transparent wind screen for motor 55 cycle side cars comprising in combination a sheet of transparent flexible material; a frame for said sheet comprising a strip of resilient metal along its upper edge; a strip of resilient metal along its lower edge of greater strength than the upper strip, and rigid members at the other two edges, said 60 framed sheet being normally flat but adapted to be bent to curved form; brackets on the side car body for holding said screen in its curved form; means whereby said screen may be readily detached from said bracket 65 so that it will resume its normally flat posi-

tion when the passenger requires to leave or enter the side car; and means at points a considerable distance below the lower edge of the screen whereby the screen when held upon said bracket may be tilted over the 70 passenger's head to form a rain hood; substantially as and for the purpose specified.

4. A transparent wind screen for motor 75 cycle side cars comprising in combination a sheet of transparent flexible material; a frame for said sheet comprising a strip of resilient metal along its upper edge; a strip of resilient metal along its lower edge of greater strength than the upper strip, and rigid members at the other two edges, said 80 framed sheet being normally flat but adapted to be bent to a curved form; brackets on the side car body for holding said screen in its curved form; means whereby the said screen may be readily detached from 85 said bracket so that it will resume its normally flat condition when the passenger requires to leave or enter the side car; means at points a considerable distance below the lower edge of the screen whereby the screen 90 when held by the said bracket may be tilted over the passenger's head to form a rain hood; means for locking the screen in various angularly adjusted positions; and means for adjusting the position of the 95 screen vertically.

5. A transparent wind screen for motor 100 cycle side cars comprising in combination a screen proper of curved form; brackets for mounting said screen on the side car body; means connecting said screen and brackets whereby the screen may be tilted over the passenger's head to form a rain hood; and means for securing the normally 105 vertical edges of the screen to the side car body; for the purpose specified.

6. A transparent wind screen for motor 110 cycle side cars comprising in combination a sheet of transparent flexible material; a strip of resilient metal along its upper edge; a strip of resilient metal along its lower edge of greater strength than the upper strip; brackets for mounting said screen on the side car body; means connecting said 115 screen and brackets whereby the screen may be tilted over the passenger's head to form a rain hood; means for locking the screen in various angularly adjusted positions; means for adjusting the position of the screen vertically; and means for securing 120 the normally vertical frame members to the side car body; for the purpose specified.

7. A transparent wind screen for motor 125 cycle side cars comprising in combination a screen proper of curved form; brackets for mounting said screen on the side car body; means connecting said screen and brackets at points considerably below the lower edge of the screen whereby the screen may be tilted over the passenger's head to form a 130

rain hood; a flexible apron; and a resilient flexible metal member within the edge of the apron; for the purpose specified.

brackets whereby the screen may be tilted over the passenger's head to form a rain hood; means for locking the screen in various angularly adjusted positions; means for adjusting the position of the screen vertically; a flexible apron; and a resilient flexible metal member within the edge of the apron; for the purpose specified. 15

8. A transparent wind screen for motor
cycle side cars comprising in combination a
sheet of transparent flexible material; a strip
of resilient metal along its upper edge; a
strip of resilient metal along its lower edge
of greater strength than the upper strip;
brackets for mounting said screen on the side
car body; means connecting said screen and

In testimony whereof I affix my signature. 20

CHARLES ARTHUR EASTING.
